UNITED STATES PATENT OFFICE.

ADDISON T. WENTWORTH, OF BEDFORD, IOWA, ASSIGNOR OF NINE-FOURTEENTHS TO F. L. ARTHAUD, OF SAME PLACE.

ADDRESSING-MACHINE.

SPECIFICATION forming part of Letters Patent No. 649,973, dated May 22, 1900.

Application filed May 18, 1899. Serial No. 717,339. (No model.)

To all whom it may concern:

Be it known that I, ADDISON T. WENTWORTH, a citizen of the United States, residing at Bedford, in the county of Taylor and 5 State of Iowa, have invented a new and useful Addressing-Machine, of which the following is a specification.

This invention relates to addressing or mailing machines, and has for one object to provide 10 a new and useful machine of this character designed for addressing newspapers, letters, and all printed matter to be sent through the mails.

To this end the invention primarily contemplates 15 an addressing-machine so constructed as to provide simple and efficient means for running out a paper strip containing a number of names and post-office addresses in successive order, pasting or gumming the strip, 20 severing the individual labels from the strip, and stamping the same upon the mail-matter to be addressed, and then automatically resetting itself for the next name and address, the said operation being accomplished by manipulating 25 the machine in the same manner as an ordinary hand-stamp.

A further object of the invention is to construct the machine so that the same may be employed in connection with a single- or double 30 list of names and addresses.

With these and other objects in view as the nature of the invention is better understood the same consists in the novel construction, combination, and arrangements of parts hereinafter more fully described, illustrated, and 35 claimed.

The essential features of the invention are susceptible to a number of modifications without departing from the spirit or scope thereof; 40 but the preferred embodiment of the different improvements is shown in the accompanying drawings, in which—

Figure 1 is a perspective view of a hand addressing-machine constructed in accordance 45 with the present invention. Fig. 2 is a horizontal sectional view on the line 2-2 of Fig. 1. Fig. 3 is a central vertical longitudinal sectional view of the machine. Fig. 4 is a detail side elevation exposing the gearing for 50 the feeding and pasting rollers. Fig. 5 is a

detail in perspective of the stationary ledger-blade of the cutting mechanism. Fig. 6 is a detail in perspective of the feeding-pawl of the feeding mechanism, showing in dotted lines the position of the engaging lug when 55 the feeding-pawl is designed to coöperate with the outer ratchet-disk having the least number of notches. Fig. 7 is an enlarged detail sectional view of the supply-reel, showing the manner of securing one end of the paper strip 60 thereto.

Like numerals of reference designate corresponding parts in the several figures of the drawings.

Referring to the accompanying drawings, 65 the numeral 1 designates an open casing provided with the opposite parallel vertical side walls 2 and with a flat bottom plate 3 connecting said side walls at the lower edges thereof and presenting a flat surface to rest 70 upon the mail-matter to be addressed when the machine is placed thereon. The said casing 1 is open at its upper side and is provided at the opposite ends thereof with front and rear upstanding arm extensions 4 and 5, respectively, the front upstanding arm extension 4 being longer than the rear extension-arm 5 and provided in the inner closed side thereof with a vertically-disposed guide-slot 6, the function of which will be presently referred to. 75

The flat bottom plate 3 of the opening of the casing 1 of the machine terminates short of one end of the casing, and between this end and the contiguous end of the flat bottom plate the casing is provided with a vertical guideway 7, leading upward from the bottom thereof and formed by the vertical slots 8 in the side walls 2 of the casing. The 85

said vertical guideway accommodates for 90 movement therein a horizontal vertically-reciprocating knife-platen 9, preferably rectangular in cross-section and having the extremities thereof slidably engaging in the side slots 8. To insure a proper guiding of the 95 knife-platen 9 within the guide-slots, the ends of said platen have a rabbeted engagement 10 with one edge of said slots, as is plainly shown in Fig. 4 of the drawings, such engagement serving to properly hold the knife- 100

platen in place, so as to prevent longitudinal movement or displacement thereof while being reciprocated within the guideway. The vertically-reciprocating knife-platen 9 cooperates with the fixed ledger-blade 11, which registers within the rabbeted seat 12, formed in the casing at one end of the flat bottom plate 3, and at this point the said bottom plate is provided with an upstanding rest-flange 13, 5 forming a base for the seat 12, whereby the ledger-blade 11 may be rigidly held in a proper working position. The ledger-blade 12 is preferably detachably fastened within the casing by means of the fastening-screws 14, passing through the fixed lugs 15, projecting from opposite inner sides of the casing and engaging threaded openings 16 in the ends of the ledger-blade, as may be plainly seen from Figs. 2 and 5 of the drawings. The 10 said ledger-blade 11 is also preferably rectangular in cross-section, and in order to insure the severing or cutting of the individual labels from the continuous paper strip the said blade is slightly beveled upon its upper side, as at 17, and is also provided with an inclined cutting edge 18, which cooperates with the cutting edge of the knife-platen 9 to produce a shear cut when the said knife-platen descends through the guideway and 15 upon the paper strip projected over the inclined cutting edge 18, as shown in Fig. 3 of the drawings.

To provide for causing the opposing cutting edges of the fixed and movable knife members to properly cooperate, there is employed a pair of side-pressure springs 19, which are detachably and rigidly fastened at their upper ends, as at 20, to the inner side of the front end wall of the casing, as shown in Fig. 3 of the drawings. From their point of attachment to the front end wall of the casing the side-pressure springs 19 project downwardly at an inclination, and the lower free portions of the said springs extend diagonally across the guideway 7, contiguous to the ledger-blade 11 and directly in the path of the vertically-movable knife-platen 9. As said knife-platen 9 descends the same engages the lower free end portions of the pressure-springs 25 19 and presses said springs back out of the way at one side of the guideway; but said springs continue to exert a pressure against one side of the platen 9, so as to forcibly press the same in a direction toward and against the ledger-blade 11, so that the opposing cutting edges will preserve their proper working relation when operating upon the strip. Upon the ascent of the knife-platen 9 the side-pressure springs 19 spring back to their normal 30 positions across the guideway 7.

The vertically-movable knife-platen 9 has projected from the upper side thereof a pair of vertically-movable stems 21. These stems are rigidly fitted at their lower ends to the 35 knife-platen and work through slide-openings 22, formed in a transverse guide-bar 23, connecting the side-walls of the casing at the

base of the front upstanding tubular arm extension 4 of the casing. The said transverse guide-bar 23 also has connected thereto a retractile spring 24, the lower end of which spring is connected at 25 to the platen 9, whereby the spring will serve to normally elevate or retract the knife-platen to a position at the upper end of the guideway 7 therefor. 75

To provide for the depression or downward movement of the knife-platen 9, the upper ends of the stems 21 are engaged, respectively, by the opposite end portions of a presser-head 26, having a wear-plate 27 and formed integrally at one end of a flat handle-core 28, the other end of which plate is provided with a cross-bar 29, having at the extremities thereof the pivot-ears 30, which are pivotally bolted or fastened, as at 31, to the opposite side portions of the rear upstanding arm extension 5 of the casing. The handle core-plate 28 constitutes a portion of the handle and has fastened, respectively, to the upper and lower sides thereof the handle pieces or sections 32 and 33, respectively. The upper and lower handle pieces or sections 32 and 33 are rounded to produce a cylindrical hand-grasp which may be readily grasped by the hand of the operator when manipulating the machine. 95

When the machine is in use, the hand-grasp extends at an inclination across the space between the front and rear arm extensions 4 and 5 of the casing, and to provide for holding the hand-grasp in operative position the same has slidably fitted within the unpivoted end thereof a slidable retaining-bolt 34, the outer end 35 of which bolt is normally projected beyond the unpivoted end of the hand-grasp, so as to extend through and work within the vertical guide-slot formed in the inner side of the front arm extension 4. At its inner end the slidable retaining-bolt 34 is provided with an offstanding finger-pin 36, working in and exposed through a slot 37 of the hand-grasp, and a coil pressure-spring 38 is set within a spring-recess 39, also formed in the upper handle of the member, said pressure-spring bearing at one end against the retaining-bolt 34 to provide for normally projecting the outer end thereof through the guide-slot 6. With the retaining-bolt engaged in the guide-slot 6 the handle is locked in place while being permitted a free up-and-down movement to provide for the necessary reciprocation of the knife-platen 9; but should it be desired to disconnect the handle from the front arm extension of the casing, so as to permit free access to the interior of the casing through the open upper side thereof, 115 it is simply necessary to draw upon the finger-pin 36 to provide for withdrawing the outer end of the retaining-bolt from the slot 6.

The paper strip 40, containing thereon the names and addresses in successive order, is 130 rolled upon a supply-reel 41. The supply-reel is designed to be supported transversely within the open upper side portion of the casing, and essentially consists of a drum 42

and the circular guard heads or flanges 43, fitted to the ends of the drum, so as to prevent the paper strip from working off of the same. The drum or body 42 of the reel is 5 preferably provided with the longitudinal rod-groove 44, which detachably receives a holding-rod 45, inserted through one of the guard heads or flanges 43 and adapted to engage over one end of the paper strip to de-
10 tachably fasten the same to the drum, and to assist in properly attaching one end of the paper strip to the drum of the reel a clip-plate 46 is fastened at one edge to the periphery of the drum and overhangs the rod-
15 groove 44 and the rod therein. The unfastened edge of the clip-plate 46, which overhangs the rod-groove, permits of the ready insertion of one end of the paper strip therein, as may be readily seen from the drawings.
20 The supply-reel 41 is revolvably and detachably supported in place in the casing by a detachable spindle 47. The spindle 47 is withdrawable from the drum or body 42 of the reel, and the opposite end portions of
25 said spindle detachably and loosely engage in the bearing-openings in the side walls of the casing, and at one end the spindle 47 is provided with a finger-knob 48 to permit of the reel being turned by hand to assist in
30 properly adjusting the paper strip.

The too-rapid rotation of the supply-reel is prevented by means of a tension-spring 49, loosely coiled upon the spindle 47 and interposed between one end of the reel and the
35 adjacent side wall of the casing. In other words, the spring 49 places a tension upon the supply-reel, so that the paper strip is kept reasonably taut during the feeding thereof to the cutting mechanism.

40 The feeding of the paper strip is accomplished through the medium of a pair of upper and lower feeding-rollers 50 and 51, respectively, the upper of said feeding-rollers 50 having the shaft extremities thereof working
45 in the vertically-slotted bearings 52, fitted to the opposite side walls of the casing and having arranged therein the pressure-springs 53, which provide for yieldingly holding the upper feeding-roller 50 in contact with the
50 lower roller 51. The two feed-rollers 50 and 51 are not arranged in vertical alinement, but are located below and at one side of the vertical plane of the supply-reel, so as to freely receive therebetween the paper strip 40, con-
55 taining the names and addresses. The lower feeding-roller 51 rotates in a fixed plane and is mounted upon the shaft 54, journaled in the bearings at the sides of the casing and having fitted on one end thereof a gear-wheel
60 55, the said gear meshing with a similar gear 56 on the contiguous shaft extremity of the upper feed-roller 50, whereby both rollers are caused to rotate in unison and in opposite directions to provide for the feeding of the
65 paper strip toward and over the stationary ledger-blade 11. The shaft extremity of the lower feeding-roller 51, opposite the cog-gear

55, has fitted thereon a finger-button 51^a, which permits of manual turning of the feeding-rollers when the paper strip is being ad-
justed within the machine, and at the same end the shaft of the lower feeding-roller has mounted thereon a frame or spaced parallel ratchet-disks 58 and 59, respectively. The ratchet-disks 58 and 59 are respectively of
70 75 different sizes and have a different number of peripheral notches, either of said ratchet-
disks being brought into play, according to whether a single or a double list of names and addresses is being fed through the machine. 80

Coöoperating with either of the ratchet-disks 58 and 59 is a pawl-lever 60, the lower free end of which lever plays within the annular groove between the two disks 58 and 59 and is provided contiguous to such end with a lat-
85 teral engagement-lug 61, adapted to engage with the peripheral notches of one of the disks. The said lug 61 projects from the inner side of the pawl-lever when the inner ratchet-disk 58 is used, and vice versa when
90 the outer disk 59 is employed, as indicated by the full and dotted lines in detail Fig. 6 of the drawings. The pawl-lever 60 works within an offstanding U-shaped keeper 61^a, projected from one side of the machine-casing and is
95 pivotally connected at its upper end, as at 62, to one end of a walking-lever 63. The walking-lever 63 is pivoted intermediate its ends, as at 64, on the exterior of the machine-casing,
100 at one side thereof, and a normal separation
of this lever and the pawl-lever is maintained by means of a coil-spring 65, interposed be-
tween the two levers and having its separate arms respectively connected thereto. The
105 pressure of the spring 65 serves to hold the free end of the pawl-lever normally engaged
with one of the ratchet-disks, so that the lug
110 61 will successively engage the peripheral notches thereof at the end opposite its con-
nection with the pawl-lever 60. The walk-
115 ing-lever 63 is pivotally connected to one end of a slotted link 66, which slidably engages
the headed stud 70, fitted to one end of the vertically-movable knife-platen 9 and mov-
able therewith, and contiguous to the upper
120 end of one of the slots 8 the casing has pro-
jected therefrom an offstanding stop-pin 71,
which arrests the upward movement of the
end of the walking-lever carrying the slotted
link when the knife-platen is drawn to the
125 upper end of the guideway by the retractile
spring 24.

By reason of the connections described it
will be obvious that upon depressing the
knife-platen 9 the walking-lever 63 will be
130 swung in a direction for drawing back the
free end of the pawl-lever to throw the lug
61 thereof in engagement with the next suc-
ceeding tooth or notch of the knife-platen.
Under the influence of the retractile spring
24 the walking-lever and the pawl-lever will
move in an opposite direction, thereby pro-
viding for automatically rotating or feeding
the rollers a sufficient distance to advance the

strip of paper for exposing another label within the guideway, so as to be cut off by the knife-platen and stamped upon the newspaper or other mailing-matter.

5 The lower feeding-roller 51 is surrounded at its lower side by a semitubular guard 72, having a plurality of openings 73 therein, and contiguous to said lower feeding-roller is arranged a paste-roller 74. The paste-roller 10 is also mounted transversely of the machine-casing and has mounted on one of its shaft extremities a gear-wheel 75, between which and the gear 55 is interposed an idler-gear 76, whereby all of the rollers will be geared 15 together for simultaneous rotation through the medium of the feeding mechanism just described.

The paste is supplied to the paste-roller 74 from a paste-receptacle 77. The paste-receptacle 77 is approximately rectangular-shaped and registers within the rear end portion of the open casing, so as to rest therein upon the flat bottom plate 3 thereof. The receptacle 77 is provided at the top thereof with a hinged 20 cover 78 and has extended from the bottom portion thereof a feed-spout 79, which projects upwardly to a slight incline, so that the mouth thereof will lie in a proximal relation to one side of the paste-roller 74 and will be 25 covered by said paste-roller, so as the latter rotates it will take up the supply of paste and transfer the latter to the reverse side of the paper strip 40, which is fitted thereover. The paste-receptacle 77 is detachably locked 30 in place through the medium of a latch-plate 80. The latch-plate 80 is pivotally mounted intermediate its ends, as at 81, on the outer side of the paste-receptacle and is provided at its upper end with an outturned finger-flange 82 and at its lower end with a hook 83, working over a guide-pin 84 and adapted to 35 detachably engage the catch-lug 85, projecting from an upstanding flange at the rear end of the machine-casing, contiguous to the bottom plate thereof, said flange also serving as a retaining-ledge to prevent outward displacement of the paste-receptacle. A spring 40 86, interposed between the finger-flange 82 and the outer side of the paste-receptacle, 45 provides for normally holding the latch-hook 83 in engagement with the lug 85.

The rest-flange 13 at one end of the flat bottom plate 3 has fitted to the upper edge thereof a plurality of regularly-spaced inclined wire-delivery fingers 87. These fingers 50 extend from one side of the paste-roller 74 to a point contiguous to the inclined cutting edge 18 of the ledger-blade and provide a surface over which the strip is fed, which obviates the possibility of the paste accumulating or clogging in such manner as to prevent the free passage of the paper strip. Transverse guide-rods 88 and 89 are arranged, respectively, above the paste-roller 74 and the 55 lower ends of the delivery-fingers 87, and the paper strip passes beneath these guide-rods, so that the same is prevented from puckering

up and is maintained in proper relation to the ledger-blade 11, over which it is worked.

From the foregoing it is thought that the 70 construction, operation, and many advantages of the herein-described addressing-machine will be readily apparent to those skilled in the art, and it will be understood that changes in the size, shape, proportion, and 75 minor details of construction may be resorted to without departing from the spirit or sacrificing any of the advantages of the invention.

Having thus described the invention, what is claimed is—

1. In an addressing-machine, the casing provided with a guideway, a ledger-blade fitted to the casing, a spring-retracted reciprocating knife-platen, a hand-grasp arranged at the top of the casing and pivoted at one end to 85 one part of the casing, said hand-grasp being arranged to depress the knife-platen, a spring-projected retaining-bolt mounted within the unpivoted portion of the hand-grasp, and having its projecting end slidably interlocked with the opposite part of the casing, and feeding mechanism for the paper strip having an operative connection with the knife-platen, substantially as described.

2. In an addressing-machine, the casing provided with a guideway, a ledger-blade fitted to the casing at one side of the guideway, a reciprocating knife-platen slidably mounted within the guideway and provided with a pair of upwardly-extending stems, a spring for 90 normally retracting the knife-platen, a hand-grasp pivotally connected at one end to the casing, and having its opposite end bearing upon the stems of the knife-platen, a slidably interlocking connection between the unpivoted end of the hand-grasp and the casing, and the feeding mechanism for the paper strip, 95 substantially as set forth.

3. In an addressing-machine, the casing provided at the upper side thereof with upstanding front and rear arm extensions, one of which is provided with a vertical guide-slot, said casing being further provided with a vertical guideway, the ledger-blade, a spring-retracted knife-platen slidably mounted within the guideway and having upwardly-extending stems, a vertically-movable hand-grasp pivotally mounted at one end on the rear arm extension of the casing and having its opposite end bearing upon the platen-stems, and a slideable spring-projected retaining-bolt mounted within the hand-grasp and having the outer projecting end thereof engaged within the guide-slot of the front arm extension of the casing, and feeding mechanism for the paper strip, substantially as set forth.

4. In an addressing-machine, the casing having a vertical guideway and an arm extension projecting from its upper side and having a vertical guide-slot, of a ledger-blade, a spring-retracted knife-platen working within the guideway, and having upwardly-extending stems, a hand-grasp pivotally supported at one end upon the casing and provided at

its opposite end with a presser-head bearing upon the said stems, a slidable spring-projected retaining-bolt mounted within the hand-grasp and having the outer projecting end thereof working in the guide-slot of said guide extension, and the feeding mechanism for the paper strip, substantially as set forth.

5. In an addressing-machine, the combination with the casing and relatively fixed and movable knife members, of a supply-reel revolvably and detachably supported within the casing and comprising a drum having end heads and provided in the periphery thereof with a rod-receiving groove, a rod in said groove and a clip-plate fastened at one edge to the drum and overhanging said groove, and feeding-rollers coöperating with the said supply-reel, substantially as set forth.

6. In an addressing-machine, the combination with the casing, and the relatively fixed and movable knife members, of a supply-reel for the paper strip, a pair of superposed feeding-rollers, one of said rollers carrying a pair of different-sized ratchet-disks, a walking-lever supported on the casing and having an operative connection with the movable knife member, and a pawl-lever also connected with the walking-lever and coöperating with either of said disks, substantially as set forth.

20 7. In an addressing-machine, the combination with the casing and the relatively fixed and movable knife members, of the supply-reel for the paper strip, a pair of superposed feeding-rollers mounted within the casing, one of said rollers carrying upon one of its shaft extremities a pair of spaced different-sized ratchet-disks, and an automatically-op-

erating pawl-lever coöperating with either of said disks, substantially as set forth.

8. In an addressing-machine, the combination with the casing and the relatively fixed and movable knife members, of the supply-reel for the paper strip, a pair of superposed feeding-rollers mounted in the casing, one of said feeding-rollers carrying upon one of the shaft extremities thereof a ratchet-disk, a walking-lever pivoted intermediate its ends on the casing and having a slotted link connection at one end with the movable knife member, and a spring-depressed pawl-lever 45 having pivotal connection with the opposite end of the walking-lever and provided with a lateral engagement-lug coöperating with the teeth or notches of the ratchet-disk, substantially as set forth.

50 9. In an addressing-machine, a casing provided at one end with an upstanding flange having a catch-lug, the cutting mechanism, the feeding mechanism, a paste-roller coöperating with the feeding mechanism, and a paste-receptacle arranged within the casing upon the bottom thereof behind said upstanding flange, said paste-receptacle being provided at its outer side with a pivotal spring-actuated latch having at its upper end a finger-flange, and at its lower end a hook detachably engaging said catch-lug.

In testimony that I claim the foregoing as my own I have hereto affixed my signature in the presence of two witnesses.

ADDISON T. WENTWORTH.
